UNITED STATES PATENT OFFICE.

JOHN JACOB PAULS, OF LYONS, IOWA.

WRITING AND DRAWING DEVICE.

SPECIFICATION forming part of Letters Patent No. 478,129, dated July 5, 1892.

Application filed February 9, 1892. Serial No. 420,900. (No model.)

To all whom it may concern:

Be it known that I, JOHN JACOB PAULS, a citizen of the United States, residing at Lyons, in the county of Clinton and State of Iowa, have invented a new and useful Writing and Drawing Device, of which the following is a specification.

The invention relates to improvements in devices for assisting in writing and drawing.

10 The object of the present invention is to provide a simple and inexpensive device adapted to be readily applied to the hand to assist a person in writing and drawing and capable of enabling a person's hand to move 15 readily and easily over the surface of paper in writing and drawing, and thereby avoid stiffness and cramps incident to rapid, strained, and continuous writing.

The invention consists in the construction 20 and novel combination and arrangement of parts hereinafter fully described, illustrated in the accompanying drawings, and pointed out in the claims hereto appended.

In the drawings, Figure 1 is a perspective 25 view of a device constructed in accordance with this invention and applied to a hand. Fig. 2 is a similar view of the device detached. Fig. 3 is a vertical sectional view.

Like numerals of reference indicate like 30 parts in all the figures of the drawings.

1 designates a curved body having a concaved upper face and provided with a centrally-arranged sleeve 2, depending from the lower face of the body and adapted to contain balls 3, one of which protrudes slightly and is adapted to rest upon the supporting surface to enable the hand in writing and drawing to move freely and steadily. The third and fourth fingers are placed in the concaved upper face of the body, which is retained to the hand by an elastic band 4 secured to the body. The sleeve 2 has its upper end closed and is provided at its lower end with an inwardly-extending flange 5, 40 which prevents the displacement of the balls.

A spiral spring 6 is interposed between the inner ball and the upper end of the tube to

form a yielding elastic cushion, whereby the device will readily give to the pressure of the hand and will not seem hard and stiff. By 50 this arrangement the lower ball, which rolls on the supporting-surface, has very little friction and the device is adapted to move freely. By using the lower ball as a center or pivot a perfect curve may be drawn, and by rotating the paper beneath the pencil and holding the latter rigid circles may be accurately drawn with a little practice.

It will be seen from the forgoing that a simple and inexpensive device is provided, that 60 the same may be readily attached to the hand and will greatly facilitate free and easy movement in writing and drawing, and that all cramps and stiffness incident to continuous and strained writing will be avoided.

The device may be advantageously employed for erasing pencil-marks by placing an ordinary pencil rubber eraser on the tube.

What I claim is—

1. A device of the class described, comprising a body adapted to be secured to the hand, a tube depending from the body, a ball arranged within the tube and projecting from the lower end of the same, and a spiral spring arranged within the tube and interposed between the body and the ball and forming an elastic cushion, substantially as described.

2. A device of the class described, comprising a curved body having a concaved upper face, a centrally-depending tube having its 80 upper end closed and provided at its lower end with a flange, balls arranged in the tube, one of the balls protruding through the lower end of the tube, a spring interposed between the balls and the upper end of the tube, and 85 an elastic band extending across the upper face of the body, substantially as described.

In testimony that I claim the foregoing as my own I have hereto affixed my signature in the presence of two witnesses.

JOHN JACOB PAULS.

Witnesses:

D. ROMER,
F. G. MASKERY.
